US0D1039502S

(12) **United States Design Patent** (10) Patent No.: **US D1,039,502 S**
(45) Date of Patent: ** Aug. 20, 2024

(54) **CONNECTOR**

(71) Applicant: **GIGALANE Co., Ltd.**, Hwaseong-si (KR)

(72) Inventors: **Young-jo Kim**, Gyeonggi-do (KR); **Hwa-yoon Song**, Gyeonggi-do (KR); **Kyung-hun Jung**, Gyeonggi-do (KR); **Hee-seok Jung**, Gyeonggi-do (KR)

(73) Assignee: **GigaLane Co., Ltd.**, Hwaseong-si (KR)

(**) Term: **15 Years**

(21) Appl. No.: **35/516,869**

(22) Filed: **Apr. 13, 2022**

(80) **Hague Agreement Data**

Int. Filing Date: **Apr. 13, 2022**
Int. Reg. No.: **DM/222270**
Int. Reg. Date: **Apr. 13, 2022**
Int. Reg. Pub. Date: **Apr. 14, 2023**

(30) **Foreign Application Priority Data**

CLAIM

The ornamental design for a connector, as shown and described.

DESCRIPTION

1. Connector

1.1: Top Perspective

1.2: Front

1.3: Back

1.4: Left

1.5: Right

1.6: Top

1.7: Bottom

1.8: Bottom Perspective

1.1 is a top perspective view of a connector; 1.2 is a front view thereof; 1.3 is a back view thereof; 1.4 is a left side

(Continued)

view thereof; **1.5** is a right side view thereof; **1.6** is a top view thereof; **1.7** is a bottom view thereof; **1.8** is a bottom perspective view thereof.
